(57) **CLAIM**

The ornamental design for the toilet seat and cover handles, as shown and described.

DESCRIPTION

FIG. 1 is a front perspective view of the toilet seat and cover handles showing my new design. The broken lines shown in this view or any other views are for illustrative purposes only and form no part of the claimed design;

FIG. 2 is a top elevation view thereof;

FIG. 3 is a left elevation view thereof;

FIG. 4 is a bottom elevation view thereof;

FIG. 5 is a rear elevation view thereof;

FIG. 6 is a front elevation view thereof;

FIG. 7 is front perspective view of the toilet seat and cover handles showing my new design but the toilet cover is abut to the toilet seat;

FIG. 8 is a front elevation view thereof; and,

FIG. 9 is a left elevation view thereof.
